UNITED STATES PATENT OFFICE.

ENOCH W. BARKER, OF WOODSTOCK, ILLINOIS.

BOOK-SUPPORT.

No. 820,170.

Specification of Letters Patent.

Patented May 8, 1906.

Application filed May 23, 1905. Serial No. 261,823.

To all whom it may concern:

Be it known that I, ENOCH W. BARKER, a citizen of the United States, residing at Woodstock, in the county of McHenry and State of Illinois, have invented new and useful Improvements in Book-Supports, of which the following is a specification.

This invention relates to a book-support for use primarily on school-desks for holding a book above the top of the desk, thus giving a pupil more room to do his regular written work in connection with the necessary text and reference books.

Without the use of such a device a pupil works at a disadvantage, as a great part of the desk is taken up by books, leaving but a small portion on which work can be done. This necessarily forces him to the extreme edge of his desk, where it is difficult for him to do justice to himself.

In the accompanying drawings, Figure 1 is a perspective view of a school-desk with one form of book-support thereon. Fig. 2 represents an elevation, on larger scale, of the book-support. Fig. 3 is a perspective view of the main bar of the folding book-rack. Fig. 4 is a similar view of the supporting-rod. Fig. 5 is a sectional view on the line 5 5 of Fig. 2. Fig. 6 is a detail view of a portion of the base 30 with the supporting-rod held therein. Fig. 7 is a view in elevation of the left side of a school-desk with a modified form of my invention applied thereto. Fig. 8 is a view in section on line 8 8 of Fig. 7. Fig. 9 is a perspective view of a further modification.

Similar letters refer to the same parts on the several figures.

Referring to Figs. 1 to 6, A indicates a base made broad and heavy on the bottom that it may retain its place on a desk or table. From the center of the base A rises a stem A', having a vertical central perforation a therein and a cross-notch a' at its top, into which perforation the lower end b³ of a supporting-rod B is placed, said rod having an offset b to fit in the notch a' and prevent the rod from being turned. The rod B extends above the offset b in an inclined direction (see Fig. 6) for some distance, a lateral angular bend b' being given it near its upper end and then back again in a horizontal direction to form a pin b².

The book-rack proper may be described in general terms as consisting of a central up-right bar D, having a transverse eye d at its upper end for the horizontal pin b² of the rod

B, also a foot-piece d' on its lower end, having an opening through which the rod B passes, and an offset d² between its ends, two shelf-pieces E, pivoted to the central bar near the lower end, on which the book rests, and other bars F so joined that the rack C may be folded into a compact form against the central bar D.

A modified form of base and supporting-rod is shown in Figs. 7 and 8. In this case 65 the base-piece consists of a strip of metal H, formed with a series of parallel semicircular hollow ribs or sockets h, notched on one side, as at h'. Holes h² in the strip H between the ribs or sockets h, are for screws, which fasten 70 the strip on the left edge of a desk, as clearly shown in Fig. 7. The base-piece or strip H may extend along the entire edge of the desk or only a portion thereof.

The rod B in the modified form of base is 75 supported by slipping its lower end b³ into one of the ribs h until the offset b enters the notch h', which holds the rod in position and prevents it from turning or rocking.

A further modification is illustrated in Fig. 80 9 and consists of a disk H⁵, centrally perforated at h⁶ for the lower end b³ of the supporting-rod B. The disk H⁵ is to be fastened in some suitable position on the top of the desk by means of pins or screws h⁷. A hole is 85 bored in the desk below the opening h⁶. When the supporting-rod B is inserted in the opening h⁶, the offset b thereon will rest between the pins or screws h⁷ and prevent the rod from turning.

Having thus described the invention, what is claimed as new is—

1. In a book-support, a socketed member having a notch arranged at an angle with relation to said socket, a rack for holding books, 95 and a supporting-rod for the book-rack having its lower end positioned in said socket and bent to provide an offset to engage in said notch.

2. In a book-support, a socketed member having a notch arranged at an angle with relation to said socket, a rack for holding books having its central bar provided with attaching means, and a supporting-rod for the book-rack having its lower end positioned in said 105 socket and bent to provide an offset positioned in said notch, said supporting-rod being secured to the central bar through the medium of said attaching means.

3. In a book-support, a socketed member 110 provided with a notch arranged at an angle with relation to said socket, a rack for hold-

ing books having the central bar thereof provided with an eye and a perforated foot-piece, and a supporting-rod for the book-rack having its lower end positioned in said socket and provided with an offset positioned in said notch, said supporting-bar being passed through the perforation of said foot-piece and having its upper end positioned in said eye.

- 10 4. In a book-support, a socketed member provided with a notch arranged at an angle with relation to said socket, a rack for holding books having a transverse eye and a per-

forated foot-piece, and a supporting-rod for the book-rack having its lower end positioned 15 in said socket and provided with an offset positioned in said notch, said supporting-rod being passed through the perforation of said foot-piece and having its upper end disposed horizontally and mounted in said eye.

20 In testimony whereof I affix my signature in presence of two witnesses.

ENOCH W. BARKER.
